UNITED STATES PATENT OFFICE.

EMILE C. REUTLINGER, OF BOSTON, MASSACHUSETTS.

WASHING MACHINE.

Application filed April 9, 1923. Serial No. 630,680.

To all whom it may concern:

Be it known that I, EMILE C. REUTLINGER, a citizen of the Republic of Switzerland, and a resident of Boston, county of Suffolk,

5 State of Massachusetts, have invented an Improvement in Washing Machines, of which the following description, in connection with the accompanying drawing, is a specification, like characters on the drawing 10 representing like parts.

This invention relates to improvements in washing machines and the general object thereof is to provide a washing machine which is more economical and efficient in operation than those which have heretofore 15 been produced.

More particularly the invention relates to washing machines having a reciprocable dasher provided with means, preferably suction cups, for engaging the clothes which are adapted to press the clothes during the movement of the dasher in one direction and to loosen up the clothes as the dasher moves in the opposite direction.

20 In washing machines of this type the dasher head is usually moved from a position above the level of the water in the tub to a position in proximity to the base of the tub. The buoyancy of the water tends normally to raise the dasher so that a greater 25 force is required to remove the dasher from the water than during its immersion in the water.

One of the objects of the invention is to 30 provide means for raising the dasher which will apply a force correlated to the resistance or weight of the dasher.

Conversely, when the dasher is depressed and particularly when it engages the clothes 35 in the tub a greater resistance is offered during its preliminary movement.

Another object of the invention is to provide means which will exert a progressively increasing force upon the dasher during its 40 downward movement.

Another object of the invention is to provide a washing machine of the character above described with a single-acting fluid motor for moving the dasher in one direction, preferably in the direction to raise 45 the dasher. By employing a single-acting

fluid motor of this character the amount of fluid required to operate the machine is greatly decreased over that which is required in the usual double-acting motors.

55

A further object of the invention is to provide leverage mechanism operable by a single-acting motor which will multiply the leverage required to raise the dasher in correlation to the weight or resistance of the dasher during the elevating movement thereof.

60

Another object of the invention is to provide a washing machine having a single-acting fluid-actuated motor for moving the dasher in one direction with spring-actuated means acting progressively to increase the force applied to the dasher when moved in the opposite direction.

65

A further object of the invention is to provide a single-acting fluid-actuated motor with valve mechanism controlled by the movement of the dasher in such a manner that the valves will be actuated only as the dasher approaches the upward and downward limits of its movement.

70

A further object of the invention is to provide a fluid-actuated motor for a washing machine with novel valve-actuated mechanism capable of permitting the exhaust valve to close in advance of the opening of the inlet valve whereby a saving of water 80 may be effected.

75

A further object of the invention is to provide a fluid-actuated motor of the character described with means acting upon the exhaust 85 from the motor to control the speed of the motor.

80

A further object of the invention is to provide a washing machine of the character described with a fluid-actuated motor in which the cylinder and piston may be removed and replaced so that different sizes of cylinders and pistons may be employed for different water pressures.

90

A further object of the invention is to provide means for rotating the dashers intermittently but not positively, preferably, but not necessarily, in a single direction.

95

A further object of the invention is to provide novel means for imparting a rotative movement to the dasher head including

100

a frictional instrumentality capable of permitting slippage if substantial resistance is imposed against the rotative movement of the head.

5 A further object of the invention is to provide novel means for rotating said head including a frictional instrumentality which is only operable to rotate the head during the reciprocating movement of the dasher.

10 A further object of the invention is to provide independently yieldable supporting means for suction cups forming a part of the dasher head.

15 A further object of the invention is to provide a washing machine having a fluid-actuated motor which is so arranged that the mechanism is never on a dead center and can, therefore, always be readily started.

20 Other objects and features of the invention will more fully appear from the following description and the accompanying drawings and will be particularly pointed out in the claims.

25 A preferred embodiment is illustrated in the accompanying drawings, in which,

Fig. 1 is a side elevation of a washing machine, embodying the invention, set upon a tub which is shown in section, a portion of 30 the dasher head being broken away and shown in vertical section;

Fig. 2 is an enlarged detail view, mainly in vertical section, of a preferred single-acting motor of the type illustrated in 35 Fig. 1;

Fig. 3 is a detail view, mainly in vertical section, through the dasher head illustrating the means for imparting rotative movement thereto, the suction cups of said head being 40 omitted;

Fig. 4 is a detail view in vertical section of the end of the valve casing of the motor, showing in section a cylinder of large diameter secured to said casing adapted to be 45 used upon fluid systems having low pressures and showing in dotted lines a cylinder of smaller diameter adapted to be substituted when the motor is connected to high pressure systems.

50 The washing machine is illustrated in Fig. 1 as being mounted upon a tub having a bottom 1 and vertical sides 2 which may be of the usual type which are found in laundries and kitchens. The washing machine comprises a casing having sides 3 and a top 4 and ends 5 which preferably are made of cast metal and provided with a removable cover not shown. The lower ends of the sides 5 desirably are provided with inturned 55 flanges 6 to which are secured blocks 7 having dove-tail grooves to receive arms 8 of brackets 9 provided with bifurcated ends 10 adapted to embrace the walls 2 of the tub.

60 These bifurcated ends may be provided with fastening devices for securing the same to 65 the tub, but preferably are of sufficient length to enable the entire machine to be raised if the dashers encounter an undue obstruction which would be likely to injure the mechanism of the washing machine.

70 The dasher of the washing machine comprises a preferably vertical dasher bar 11 having at its lower end a rotatable head which as shown comprises a plate or spider 12 which carries a plurality of plungers, 75 preferably in the form of suction cups 13.

80 In the preferred construction disclosed herein the dasher is given a vertically reciprocating movement, being raised by a single-acting pump which operates upon said dasher through a leverage system which acts with increasing leverage as the dasher is raised. The downward movement of the dasher may be produced by gravity alone, but preferably resilient means are employed 85 which act with progressively increasing force upon the dasher during its downward movement. In the particular mechanism illustrated the upper end of the dasher bar 11 is connected to the lower end of a flexible 90 member or chain 14, the upper end of which passes around, or as shown is connected to a rotatable member 15 having a cam face 16 which engages the flexible member 14.

95 The same or preferably another flexible member or chain 17 passes over another cam surface upon the rotatable member 15 and is connected at its opposite end to the arm 18 of a bell crank lever the end of which arm is provided with a cam surface 19 likewise 100 adapted to engage the flexible member or chain 17.

105 The bell crank lever is pivoted upon a stud 20 extending inwardly from the side 3 of the casing and the other arm of the bell crank lever preferably is provided with a V-shaped notch 21 to receive a knife edge 22 upon the end of the piston rod 23 of the single-acting fluid-actuated motor.

110 The piston head, which is connected to the piston rod 23, may be of any suitable character, but preferably comprises a cup-shaped device 24 of flexible material (see Fig. 3) clamped between collars 25 and 26 which are secured upon the reduced end 27 of the piston rod by a suitable nut 28. The piston head is reciprocably mounted in a cylinder 29 which may be of brass, steel, or other suitable material, and is provided with a neck 30 having a screw threaded outer wall 120 by means of which it is connected to a valve casing 31. By reason of this construction the cylinder, the piston and its rod can readily be removed and a larger or smaller cylinder and piston substituted therefor in accordance with the fluid pressure of the system to which the motor is attached.

125 It will be understood that fluid motors of this type are usually actuated by the water upon the usual systems which are installed 130

in houses and as the pressure in the various water systems varies greatly it is desirable that a suitable piston and cylinder may be employed to operate properly upon the pressure present in the pipes of the laundry or kitchen in which the washing machine is installed. This feature, therefore, of providing replaceable cylinders and pistons is of great importance in order to obtain the proper operation of the machine and also in order to enable ready repair and replacement of the cylinder or piston when either becomes worn.

Any suitable valve mechanism may be employed for controlling the supply and exhaust of the fluid to the motor, but preferably a special mechanism is provided as will hereinafter be more fully described.

In the operation of the device the buoyancy of the water tends normally to raise the dasher so that less power is required to elevate it while it is submerged than that which is required to raise it afterward particularly where the head of the dasher is provided with suction cups which enclose a considerable amount of water. By properly proportioning the lever arms 21 and 18 of the bell crank lever and properly designing the cams 19, 17 and 16 of the rotatable member 15 practically the same fluid pressure force upon the piston will exert a varying lifting power upon the dasher, thus requiring a minimum amount of fluid pressure to actuate the dasher.

It is desirable that the valve-actuating mechanism for the single-acting fluid-operated motor shall be so designed that the inlet and exhaust valves will be opened and closed respectively only as the dasher approaches the limit of its stroke. One of the features of the present invention relates to novel valve mechanism which is controlled by the movement of the dasher to effect this purpose.

In the preferred construction disclosed herein the valve casing 31 comprises a cylindrical inlet section 32 and a cylindrical outlet section 33 extending at right angles to said inlet section. The inlet conduit 34 is connected by a suitable union to the inlet section 32 of the valve casing, an annular flange 35 of a valve cage or guide 36 being clamped between the abutting ends of the inlet conduit and the inlet 32 of the valve casing. The inlet end of the valve casing desirably is provided with an inwardly extending rib 37 which forms a seat for a gasket 38 which forms the valve seat. The inlet valve 39 desirably is of conoidal form having a flat base adapted to engage the valve seat 38. The valve 39 is screw threaded upon the end of a valve stem 40 and is secured thereupon by a suitable nut. The inner end of the valve stem 40 is connected by a pivotal stud 41 to the elbow of

a bell crank lever, one arm 42 of which is mounted upon a pivot 43 upon a block 44 which is located in a downward extension or nipple 45 upon the valve casing and is secured in place by a cap 46 screwed upon said nipple. The other arm 47 of the bell crank lever is provided with a downward extension 48 which is connected by a pivot 49 to the lower end of the valve stem 50 of the exhaust valve.

The exhaust valve 51 desirably is of conoidal form and provided with a flat face adapted to engage a valve seat 52 which is clamped between a shoulder upon an inwardly projecting rib of the outlet section and the abutting end of an outlet conduit 53 which is secured to the casing by a collar 54 having an inwardly extending flange engaging a complementary flange upon the outlet conduit and which is also provided with internal screw threads engaging external screw threads upon the outlet section 33 of the valve casing.

The exhaust valve 51 desirably is slidably mounted, a reduced portion 55 of the valve stem and collar 56, which is located at a short distance from the normal position of the base of the outlet valve when closed, serving to engage the valve upon downward movement of the valve stem 55 to force the valve from its seat.

As illustrated in the present construction the inlet valve is in open position with the piston ready to travel upon its working stroke. When the piston has approximately reached the end of its working stroke the exhaust valve stem 55 is forced downwardly by mechanism which will hereinafter be described, thus first moving the inlet valve 39 towards closed position before the collar 56 engages the base of the valve 51. Further movement will cause the complete closing of the inlet valve 39 and opening of the exhaust valve 51. The weight of the dasher, and in the specific construction illustrated herein also the action of the spring, will then force the piston toward the valve casing thereby causing the fluid to flow from the motor through the exhaust port, the outlet conduit 53 to the waste conduit 57 until the piston has approached the limit of its exhaust stroke, whereupon the valve-actuating mechanism hereinafter described will be actuated by the movement of the dasher to raise the stem 55 of the exhaust valve. As soon as the valve stem 55 begins its upward movement the exhaust valve is raised by the water pressure to close the exhaust port, by reason of the fact that the exhaust valve 51 is slidably mounted upon its stem; consequently, the exhaust valve will be closed before the inlet valve is forced any considerable distance from its seat. By reason of this construction, therefore, a considerable saving of the fluid or water is attained.

A further feature of the invention consists in providing means for regulating the speed of the motor by controlling the flow of fluid through the outlet. The preferred mechanism illustrated in the accompanying drawings for accomplishing this purpose comprises a nipple 58 which is screwed upon the end of the waste or discharge pipe 57 and is provided with a conduit 59 having a 5 preferably conical end 60 adapted to seat upon a complementary conical wall 61 in the end of the discharge pipe 57, the conduit 59 being secured rigidly to the nipple 58. The end 60 of the conduit 59 may be provided with a small aperture and with large 10 apertures through its cylindrical walls, the small aperture permitting a very slow flow of fluid when the end 60 of the conduit is seated against the inclined wall 61 and the 15 large apertures permitting a free flow of such fluid as escapes between the end 60 of the conduit 59 and the wall 61 when the nipple 58 is adjusted to a position to permit more or less flow of the water from the 20 motor. By turning the nipple 58 the discharge area between the head 60 of the conduit 59 and the wall 61 may be regulated to impose more or less back pressure upon the motor and thereby to regulate its speed 25 of action so that the motor may be readily controlled either to reciprocate at a rapid rate as is usual in the operation of washing machines, or at a very slow rate where delicate fabrics, such as laces, are being 30 cleansed. Thus the washing machine can be readily controlled to operate upon any character of material.

As above stated the operation of the inlet 35 and exhaust valves for the motor desirably are controlled by the movement of the dasher.

In the preferred mechanism illustrated in the accompanying drawings means, operable by the dasher, are provided to permit 40 quick opening and closing movements of the inlet and exhaust valves so that the valves are actuated only when the dasher is approaching the limits of its stroke.

As illustrated the upper end of the 45 exhaust valve stem 55 has attached to it, by a screw threaded connection, a head 62 which is connected to a reciprocating member preferably in the form of a slide 63 having a slot 64 the walls of which embrace a pivot 65 of a rocker 66 one end of which is connected by a pivotal stud 67 to the upper end of the dasher bar 11. The opposite end of the rocker 66 is provided with a laterally extending stud 68 which engages cam-shaped end portions 69 and 70 respectively of levers 71 and 72 which are fulcrumed at their opposite ends upon studs 73 and 74 seated in the side 3 of the casing.

Resilient means are provided for actuating 50 these levers. In the preferred construc-

tion the levers are connected by a helical tension spring 75 normally tending to force the cam-shaped ends 69 and 70 into engagement with the stud 68 upon the end of the rocker. The sliding member, however, is provided with a pair of lugs 76 and 77 which engage the respective levers upon the upward and downward movements of the slide, thereby removing the ends 69 and 70 of the levers respectively from engagement 75 with the stud and placing the spring 75 under tension alternately by the upward and downward movement of the rocker.

The rocker is also provided with a rigid, 80 preferably integral, downwardly extending plate 78 having upon it a cam 79 having preferably arcuate parallel faces which alternately engage a stud 80 upon an extension 63^x of the sliding member 63 and restrain the movement of the valves until the stud 80 passes beyond the end of the cam thereby preventing movement of the valves until the dasher approaches the upward and downward limits of its stroke.

The slide 63 is also provided with lugs 81 and 81^x which will be engaged and actuated by the arms 71 and 72 when these arms are moved to the upward and downward limits 95 of their movement by the lug 68 on the rocker 66. These lugs, therefore, act positively to actuate the slide in the event of sticking of one or both of the valves.

In the operation of the device the downward movement of the dasher moves the rocker 66 about its pivot 65 raising its opposite end which carries the stud 68 thereby engaging the cam-shaped end 69 of the lever 71 and raising the lever imposing a tension upon the spring 75. The opposite end of the spring being connected to the lever 72 tends to rock the lever 72 upwardly, thereby lifting the lug 79 upon the slide. Such upward movement, however, is restrained by the engagement of the stud 80 with the under face of the cam 79 upon the extension 78 of the rocker until the downward movement of the dasher has swung the plate 78 sufficiently to release the stud 80 from engagement with the cam 79, whereupon the tension of the spring acting through the lever 72 and lug 76 upon the sliding member with which it is in engagement quickly raises the slide and the valve stem 55 which is attached to it, thus closing the relief valve and opening the inlet valve. The fluid then flows through the inlet port into the cylinder and forces the piston in the opposite direction (to the right) thereby actuating the lever mechanism to raise the dasher. When the dasher approaches the limit of its upward movement the rocker 66 is moved in the other direction and the stud 68 upon its end engages the cam-shaped end of the lever 72 depressing the same and imposing tension upon the spring 75 thereby causing the lever

71 to press downwardly upon the lug 76. In the meantime the movement of the rocker 66 causes the stud 80 upon the extension 63^x of the slide to engage the upper surface of the cam 79 upon the rocker plate 78, thus restraining the downward movement of the sliding member until the dasher approaches the upward limit of its stroke, whereupon the stud 80 rides over the end of the cam 79 and the tension of the spring, acting through the lever 71 upon the stud 76 on the sliding member, forces the sliding member downwardly, thereby depressing the piston stem 55, opening the outlet valve 51 and closing the inlet valve 40. It will be remembered that the outlet valve 51 is loosely mounted upon a stem and operates during the upward movement of the valve stem 55 to close the outlet port before the inlet valve is fully opened, thereby effecting the saving of the fluid which operates the motor.

It has been stated that the single-acting motor operates to move the dasher in one direction only which, as illustrated herein, is in the upward direction. The downward movement of the dasher may be caused by gravity alone, but preferably means are provided for imposing a progressively increasing force upon the dasher as it descends so that when the dasher is engaged first by the water in the tub and afterwards by the materials being cleansed, a greater force can be imposed upon the dasher substantially in proportion to the resistance which is encountered by the dasher.

Preferably this is accomplished by resilient means which acts progressively upon the dasher with increasing leverage during its descent and conversely acts upon the dasher with decreasing leverage during its ascent.

In the preferred construction illustrated a lever 82 is fulcrumed upon a stud 83 carried by a bracket 84 extending downwardly from the side 3 of the casing. The opposite end of the lever 82 is pivotally connected by a stud 85 to the dasher bar 11. The lever 82 is provided intermediate of its ends with an upwardly extending arm 86 preferably lying in the plane of or parallel to the lever 82. Preferably the lever 82 is in the form of two parallel connected plates which extend upon opposite sides of the cylinder 29. The arms 86 of the lever are provided with V-shaped upper ends forming knife edges 87 which engage the angles of V-shaped end portions 88 of a yoke 89 having a cylindrical stem 90 which is telescopically mounted in a cylindrical member 91 which is pivotally mounted at its upper end upon a stud 92 projecting from the side 3 of the casing. A helical compression spring 93 is interposed between the collar 94 upon the upper end of the cylindrical member 91 and

the shoulder 95 presented by the upper walls 65 of the yoke 89.

During the operation of the device the raising and lowering of the dasher rocks the lever 82 about its fulcrum 83 thereby causing the V-shaped upper end of the arm or arms 86 to move through an arcuate path from substantially the full line position illustrated in Fig. 1 to the dotted line position so that during the upward movement of the dasher the effective leverage applied by the spring-actuated instrumentality to the lever 82 is progressively lessened and conversely during the downward movement of the dasher the effective leverage applied by the spring-actuated instrumentality to the lever 82 is progressively increased. Thus by the leverage mechanism which connects the piston rod 23 to the dasher the power applied to the dasher upon its upward movement is correlated to the resistance of the dasher as it rises through and from the water in the tub and during the downward movement the force applied to the dasher is correlated to the resistance imposed upon the dasher upon its entry into and progress through the water and also to the additional resistance imposed upon the dasher by engagement with the articles being cleansed.

Any suitable form of dasher head may be used. Preferably a dasher head comprising a plurality of suction cups is employed and such suction cups provided with valve mechanism which will open to permit the escape of air and water from the suction cups during the downward movement of the dasher and which will close during the upward movement of the dasher.

A further feature of the invention consists in so mounting the suction cups of the dasher head that they may yield independently upon engagement with undue obstruction as from a bunch of clothes, and a further feature of the invention consists in providing a novel mechanism for causing intermittent, but not positive, rotation of the cups either in one direction or alternately in opposite directions during the reciprocating movement of the dasher.

In the particular construction illustrated herein the lower end of the dasher bar 11 is provided with a lateral extension 96 to which a downwardly extending shaft 97 is secured, preferably by a cylindrical extension 98 of less diameter than the shaft which projects upwardly through the dasher bar extension 96 and is riveted at its upper end, the shoulder between the extension 98 and the shaft 97 abutting against the under face of the extension 96 of the dasher bar. A sleeve 99 is rotatably mounted upon the shaft 97 and desirably is provided with an upwardly extending enlarged toothed upper end 100 which engages complementary teeth upon a

sector 101 fixedly secured upon the end of the arm 82. The dasher head comprises a spider 102 preferably having radially extending channel-shaped arms 103 and provided with a hub 104 having an enlarged flange 105. A plate 106, having a hub provided with an angular recess fitted upon a complementary angular extension 107, is supported upon a retaining plate 108 which is secured to the shaft 97 by a screw 109. The plate 106 is provided with an annular flange 110 complementary to the flange 105 of the spider 102 and a friction disk 111, preferably of fibrous material, is interposed between the flanged portion of the spider and the flanged portion of the plate 106, a slight clearance being provided which will permit rotation of the spider if pressure is not imposed upon it, but when pressure is imposed upon the spider by the movements of the dasher the flange portion of the spider will engage the friction disk with sufficient force to clamp it upon the flanged portion of the plate 106 and thereby cause it to be rotated by the rotation of the sleeve 99.

While the frictional mechanism is illustrated in the present construction as being located below the sleeve it will be readily understood that by a suitable modification it may be located above the rotatable sleeve or otherwise to produce rotation of the head during the downward movement of the plunger instead of the upward movement, or if desired friction devices may be so located as to produce a non-positive oscillatory movement of the plunger.

Suitable plungers or suction cups may be secured to the spider 102 in any suitable manner. As illustrated herein means are provided for permitting the plungers or suction cups to yield upwardly independently. As illustrated herein arms 112 are fulcrumed upon studs 113 which are fixedly secured in flanges 114 of the spider arms and each arm 112 is connected at its outer end to a bell-shaped sheet metal member 115 by a bolt 116 having a head engaging the upper face of the arm and provided with a nut 117 engaging the under face of the bell-shaped sheet metal members 115. The bolt 116 extends downwardly some distance and is provided with a section 118 of smaller diameter upon which a circular valve plate 119 is secured by a nut 120. The periphery of the valve plate 119 desirably is provided with a fibrous covering 121 such as is usually used to insure proper engagement of the valve with its seat. Each of the suction cups 13 is of bell shape, the upper end being of a lesser diameter than the diameter of the bell-shaped member 115 and provided with an inwardly extending flange 122 which overlies the periphery of the valve plate 119 a considerable distance. The length of the

bolt 116 is such that when the dasher is raised the bell-shaped suction member will rest upon the upper surface of the valve 119 and close the port 123 in the upper portion of the suction member. Thus as the dasher ascends the suction cup will be sealed and retain the water which is in it until the lower edge of the suction cup is raised above the level of the water in the tub. Upon the downward movement, however, of the dasher the suction cup will be raised by the buoyancy of the water so as to unseat the flange 122 from the valve and thereby permit the air and water to escape through the port 123 during the downward movement of the dasher.

By reason of the engagement of the toothed periphery 100 of the sleeve 99 with the teeth of the sector 101 which is pivoted upon the dasher the vertical reciprocating movement of the dasher will oscillate the sector and cause rotative movement of the sleeve 99 first in one direction and then in the other. During the downward movement of the dasher the suction cups will engage the water and will be raised by the buoyancy thereof and in turn will raise the spider out of intimate contact with the friction disk 111 so that the sleeve will rotate idly. Upon the upward movement of the dasher, however, the weight of the suction cups which are then filled with water will impose a downward force upon the spider which will cause its flange 105 to clamp down upon the friction disk 111 and force it firmly against the flange 110 of the plate 106 which is secured to the sleeve so that the rotative movement of the sleeve, caused by the oscillation of the toothed sector during the movement of the dasher in the upward direction, will rotate the spider and the suction cup. If, however, the suction cups engage an obstruction, such as a bunch of clothes, sufficient slippage will occur between the spider, the friction disk and the plate 106 to prevent any injury to the clothes or undue strain upon the actuating mechanism.

As has heretofore been stated, washing machines of this type are usually actuated by the fluid pressure of the water in the usual water pipe systems of houses, apartments, etc., and such pressure varies through a very wide range from twenty-five pounds or less to one hundred twenty-five pounds or more. It is desirable, therefore, that the washing machine motor shall be so constructed that a suitably sized piston and cylinder may be employed for the water pressure which is present in the place in which the machine is to be installed.

Another feature of the present invention consists in providing means by which a cylinder and a piston which are unsuitable to the water pressure in a predetermined

place may be removed and another cylinder and piston substituted therefor. This is accomplished in the present construction by providing a plurality of interchangeable cylinders and co-operating pistons. As heretofore described the cylinder 29 is provided with a reduced end having an externally screw threaded wall which engages the screw threaded inner wall of the end 31 of the valve casing and can be readily removed. Likewise the end of the piston rod is provided with a knife edge which engages the apex of a V-shaped recess in the end of the bell crank arm 21. By simply unscrewing the cylinder 29 it can be removed and the piston rod removed with equal readiness and another cylinder and piston of proper diameter for the pressure of the system substituted. This is graphically illustrated in the enlarged detail view Fig. 4 in which the cylinder 29 is illustrated in full lines as being provided with an externally screw threaded extension 30 engaging internal screw threads of the extension 31 of the valve casing and in dotted lines a cylinder 124 of smaller diameter which likewise is provided with an externally screw threaded extension adapted to fit the screw threaded internal wall of the end 31 of the valve casing.

Suitable means are provided for arresting the action of the dasher. As illustrated herein the arm 21 of the bell crank lever which is actuated by the piston is provided near its lower end with a shouldered lug 125 which is adapted to be engaged by the shoulder 126 of a latch 127 which as illustrated is in the form of a sector pivotally mounted upon a stud 128 projecting laterally from a bracket 129 on the end 5 of the casing. The latch 127 extends through a slot in the sector and is provided with a shouldered extension 130 which engages the casing 5 when the latch is in locking position. The latch also is provided with a lever 131 by means of which it may be swung about its pivot out of engagement with the sector. This latch is so positioned as to engage the lug 125 just after the piston has made its full stroke and at the time it is starting upon its return or exhaust stroke.

In order to start the machine it is merely necessary to pull the lever 131 over to release the latch from engagement with the lug 125. Thereupon the weight of the dasher will cause it to descend and as it descends the spring 93, acting through the lever 82, will exert a progressively increasing force upon the dasher. When the cups 13 have entered the water the buoyancy of the water will force them upwardly away from the valve 119 thereby permitting the air and water to escape from the cups as they descend. During this movement the

piston rod 23 will move (to the left) in such a manner as to force the piston towards the head of the cylinder. During the descent of the piston the toothed sector 101 will rotate the sleeve 99 in one direction, but the head will be raised by the buoyancy of the water so that no substantial rotative movement will be imparted to it during the downward movement of the plunger. When the plunger approaches the limit of its downward movement the rocker 66 will be actuated sufficiently to carry the cam-shaped member 77 out of engagement with the lug upon the slide 78, thereby permitting the lever 71 to force the slide 78 downwardly, thus closing the outlet port and opening the inlet port in the manner above described. Water will then flow into the cylinder forcing the piston in the opposite direction. As the piston is progressively forced along the cylinder the leverage mechanism, which connects the piston rod with the dasher, will raise the dasher with a progressively increasing force in correlation to the resistance imposed upon it by the weight of the dasher and the water contained in the suction cups 13 which automatically seat upon the valve 119 as the piston is raised. During the raising movement of the dasher the spring-actuated instrumentality, which engages the lever 82, is swung progressively toward a position more nearly in alignment with the fulcrum 83 of the lever 82 so that the force of the spring upon the piston is progressively decreased until the limit of upward movement of the piston is reached.

By reason of the construction above described the mechanism operates in such a manner that it is never upon a dead center so that the operation will not cease unless arrested by the operator.

The speed of operation of the machine may be adjusted from a maximum to a minimum by properly adjusting the valve 67 which controls the effective area of the outlet port.

By reason of the construction above described a washing machine is provided which will operate at a maximum efficiency, with a minimum consumption of fluid, and may be controlled to operate at any desired rate of speed.

In this construction the dasher head can be readily removed by unscrewing the screw 109 thus enabling the washing machine to be readily placed within the tub when not in use if the capacity of the tub is not sufficient to permit the washing machine in its assembled position to be placed within the tub. Thus the machine can be readily stored when not in use.

It will be understood that the embodiment of the invention disclosed herein is of

an illustrative character and is not restrictive and that various modifications in form, construction and arrangement of parts may be made within the spirit and scope of the following claims.

Having thus described the invention, what is claimed as new, and desired to be secured by Letters Patent, is:

10. A washing machine comprising a reciprocable dasher, a single-acting fluid motor operable to move the dasher in one direction and resilient means acting to move the dasher in the opposite direction.
15. A washing machine comprising a reciprocable dasher, a single-acting fluid motor operable to move the dasher in one direction and means intermediate of said motor and dasher for varying the force applied by the motor to the dasher during the motor-actuated movement thereof.
20. A washing machine comprising a reciprocable dasher, a single-acting fluid motor operable to move the dasher in one direction and a leverage system intermediate of said motor and dasher to vary the force applied by the motor to the dasher during the motor-actuated movement thereof in correlation to the resistance imposed upon the motor by the movement of said dasher.
25. 4. A washing machine comprising a vertically reciprocable dasher and a single-acting fluid motor operable to raise said dasher against the action of gravity and means acting upon the dasher to supplement the action of gravity upon its downward movement.
30. 5. A washing machine comprising a reciprocable dasher, a single-acting fluid motor comprising a cylinder and a piston, a bell crank lever connected to said piston having a cam-shaped portion, a flexible member connected to said bell crank lever operatively engaged by said cam-shaped portion, and connected to said dasher, whereby the force applied to the piston by said motor will be varied during the motor-actuated movement thereof.
35. 6. A washing machine comprising a reciprocable dasher, a single-acting fluid motor comprising a cylinder and a piston, a bell crank lever connected to said piston having a cam-shaped portion, a flexible member connected to said bell crank lever operatively engaged by said cam-shaped portion, a rotatable member having a plurality of cams one of which is engaged by said flexible member and a flexible member connected to said dasher engaging another of said cam-shaped portions of said rotatable member, whereby the force applied to the piston by said motor will be varied during the motor-actuated movement thereof.
40. 7. A washing machine comprising a reciprocable dasher, a single-acting fluid motor operable to raise said dasher against the

action of gravity and resilient means acting to push said dasher downwardly with progressively increasing force.

8. A washing machine comprising a reciprocable dasher, means for positively moving the dasher in one direction, a lever connected to said dasher and spring-actuated means engaging said lever mounted to act upon said lever progressively at different effective distances from the fulcrum of said lever during the reciprocation of the dasher, whereby the force of the spring applied to the dasher will be varied in correlation to the resistance imposed upon the dasher.

9. A washing machine comprising a reciprocable dasher, means for positively moving the dasher in one direction, a lever connected to said dasher provided with an arm extending at an angle to the axis of said lever in the plane of its movement, a spring-actuated instrumentality mounted upon a fixed pivot and having means engaging said arm at a distance from the axis of said lever, whereby the line of direction through which the force of the spring is applied to said lever will move toward and from the fulcrum of said lever during the reciprocation of said dasher.

10. A washing machine comprising a reciprocable dasher, means for positively moving the dasher in one direction, a lever connected to said dasher, an arm extending at an angle to the axis of said lever in the plane of its movement and provided with a knife edge, a spring-actuated instrumentality having one end engaging said knife edge and the other end mounted upon a fixed pivot so located that the line of direction through which the force of the spring is applied to said lever will move toward and from the fulcrum of said lever during the reciprocation of said dasher.

11. A washing machine comprising a reciprocable dasher, a single-acting fluid motor operable to move the dasher in one direction, lever mechanism intermediate of said motor and dasher acting to vary the force applied by the motor to the dasher during the motor-actuated movement thereof in correlation to the resistance of the dasher, a lever connected to said dasher provided with an arm extending at an angle to the axis of said lever in the direction of its movement, a spring-actuated instrumentality mounted upon a fixed pivot having a free end engaging said arm and movable thereby to cause the effective force of said spring to lessen during the upward movement of said dasher and to increase during the downward movement of said dasher whereby the force applied to said dasher will be correlated to the resistance imposed by the dasher upon the fluid motor.

12. A washing machine comprising a

vertically reciprocable dasher having a rotatable head provided with clothes-engaging means, oscillatory means operable by the reciprocation of said dasher to rotate said head, a single-acting fluid motor operable to raise said dasher, lever mechanism intermediate of said motor and dasher acting to vary the force applied by the motor to the dasher during the motor-actuated movement thereof in correlation to the resistance of the dasher and a spring-actuated instrumentality acting upon said dasher with progressively increasing force during the downward movement of said dasher.

13. A washing machine comprising a tub, a dasher including a dasher bar and a rotatable head mounted thereon and located within said tub, means for reciprocating said dasher vertically, means for rotating said head during the upward movement of the dasher including a frictional instrumentality mounted upon said head capable of permitting slippage if substantial resistance is imposed against the rotative movement 25 of said dasher head.

14. A washing machine comprising a tub, a dasher including a dasher bar and a rotatable head mounted thereon and located within said tub, means for reciprocating said dasher vertically, means for imparting rotative movement to said dasher head including an oscillatory device mounted upon said head, and frictional clutch members respectively upon said oscillatory device and said head operable to rotate said head only during the upward movement of said dasher.

15. A washing machine having a dasher comprising a dasher bar and a rotatable dasher head mounted thereon, means for reciprocating said dasher vertically, a toothed sector pivotally mounted on said dasher bar having a pivotally mounted arm, a sleeve rotatable on said dasher bar having teeth engaging said sector and co-operating frictional members carried respectively by said sleeve and said head and caused to engage during the movement of said dasher to rotate said head in one direction.

16. A washing machine having a dasher comprising a dasher bar and a rotatable head mounted thereon and means for reciprocating said dasher vertically, a toothed sector pivotally mounted upon said dasher bar having a pivotally mounted arm, a sleeve rotatably mounted on said dasher bar having teeth engaging said sector, frictional members on said sleeve spaced apart from each other and a co-operating frictional member on said head intermediate of the frictional members upon said sleeve acting to engage one of the frictional members on said sleeve upon downward movement of the dasher to cause rotation of the head in one direction and the other of said frictional members on said sleeve upon the up-

ward movement to rotate said head in the opposite direction.

17. A washing machine having a vertically reciprocable dasher comprising a dasher bar and a rotatable head located at the lower end thereof having a plurality of suction cups, means for imparting rotative movement to said head including an oscillatory device and frictional clutch members respectively upon said oscillatory device and said head acting during the upward movement of said dasher to rotate said head.

18. A washing machine having a vertically reciprocable dasher comprising a dasher bar and a rotatable head having a plurality of suction cups provided with valves operable to open upon downward movement and to close upon upward movement of said dasher, a toothed sector pivotally mounted upon said dasher bar having a pivotally mounted arm, a sleeve rotatably mounted on said dasher bar having teeth engaging said sector and co-operating frictional members carried respectively by said sleeve and head and caused to engage only during the reciprocation of said dasher to impart rotation to said head.

19. A washing machine having a vertically reciprocating dasher comprising a dasher bar and a rotatable head having a plurality of suction cups provided with valves operable to open upon downward movement and to close upon upward movement of said dasher, a single-acting fluid motor operable to move said dasher in one direction, a leverage system intermediate of said motor and dasher to vary the force applied by the motor to the dasher during the motor-actuated movement thereof in correlation to the resistance imposed upon the motor by the movement of said dasher, a spring-actuated instrumentality acting with progressively increasing force upon said dasher during its downward movement, means for imparting rotative movement to said head including an oscillatory device and frictional clutch members respectively upon said oscillatory device and said head acting to transmit rotative movement to said head during the reciprocating movement of the dasher.

20. A washing machine having a vertically reciprocable dasher comprising a dasher bar and a rotatable head having a plurality of suction cups provided with valves operable to open upon downward movement and to close upon upward movement of said dasher, means for raising said dasher, a lever pivotally connected to said dasher bar and having a fixed fulcrum at a distance therefrom, an arm extending at an angle to the axis of said lever in the plane of its movement, a spring-actuated instrumentality mounted upon a fixed pivot and having means engaging said arm at a dis-

- tance from the axis of said lever whereby the line of direction through which the force of the spring is applied to said lever will move toward and from the fulcrum of said lever during the reciprocation of said dasher, a toothed sector on said lever, a sleeve rotatably mounted on said dasher bar having teeth engaging said sleeve and co-operating frictional members respectively upon said sleeve and head caused to engage during the reciprocation of said dasher and thereby to impart rotative movement to said head.
21. A washing machine having a vertically reciprocable dasher, a single-acting fluid motor operable to move the dasher in one direction comprising a cylinder and a piston reciprocable therein, means connecting said piston with said dasher, inlet and outlet valves for said cylinder, means connecting said valves to cause reverse opening and closing movements of the respective valves and means operable by the vertical reciprocation of said dasher to actuate said valves and resilient means acting to move the dasher in the opposite direction.
22. A washing machine having a vertically reciprocable dasher, a single-acting fluid motor operable to move the dasher in one direction comprising a cylinder and a piston reciprocable therein, means connecting said piston with said dasher, inlet and outlet valves for said cylinder, a reciprocable member connected to said valves, spring-actuated members operable to move said reciprocable member in opposite directions and a rocker connected to said dasher rod having means for controlling the action of said spring-actuated members upon said reciprocable member and acting to prevent movement of said valves until said dasher has approached the limits of its upward and downward movements respectively.
23. A washing machine having a vertically reciprocable dasher, a single-acting fluid motor operable to move the dasher in one direction comprising a cylinder and a piston reciprocable therein, means connecting said piston with said dasher, inlet and outlet valves for said cylinder, a reciprocable member connected to said valves, a pair of members connected by a spring and operable respectively to move said reciprocable member in opposite directions, a rocker connected to said dasher and having means engaging said spring-actuated members acting to render the spring effective alternately upon each of said members and co-operating means upon said rocker and reciprocating member for preventing movement of said valves until the dasher has approached the limits of its upward and downward movements respectively.
24. A washing machine having a vertically reciprocable dasher, a single-acting fluid
- motor operable to move the dasher in one direction comprising a cylinder and a piston reciprocable therein, means connecting said piston with said dasher, inlet and outlet valves for said cylinder, means including a bell crank lever connecting the valve stems of said valves, the exhaust valve having a limited free movement on its stem enabling said exhaust valve to close in advance of the opening of said inlet valve thereby effecting a saving in the amount of fluid required to operate the motor.
25. A washing machine having a dasher and a single-acting fluid motor operable to move the dasher in one direction comprising a casing, valve mechanism in said casing, means operable by the movement of said dasher to control said valve mechanism, a cylinder detachably secured to said casing and a piston for said cylinder removably connected to said dasher whereby cylinders and pistons of different sizes may be employed for different fluid pressures.
26. A washing machine comprising a tub, a dasher comprising a head located within said tub and provided with a plurality of vacuum cups, each cup having an arm pivotally mounted upon said head, resilient means for permitting each cup carrying arm to yield independently and means for reciprocating said dasher.
27. A washing machine having a dasher comprising a dasher bar, a head including a plate, independent arms pivotally mounted on said plate, suction cups upon the respective arms and resilient means mounted on said plate engaging the respective arms acting normally to force said arms into engagement with said plate and to permit independent yielding movement of each of said cup carrying arms.
28. A washing machine having a dasher comprising a dasher bar, a head including a plate, independent arms pivotally mounted on said plate, suction cups upon the respective arms and resilient means mounted on said plate engaging the respective arms acting normally to force said arms into engagement with said plate and to permit independent yielding movement of each of said cup carrying arms and means for rotating said head including a frictional instrumentality mounted on said head capable of permitting slippage if substantial resistance against rotative movement is encountered by said suction cups.
29. A washing machine comprising a casing, a reciprocable dasher and means for actuating said dasher, means for securing the casing to a wash tub capable of permitting relative vertical movement between said casing and tub whereby the casing may be raised upon engagement of the dasher with undue resistance within the tub.

30. A washing machine comprising a casing, a reciprocable dasher and means for actuating said dasher, means for securing the casing to a wash tub comprising brackets having adjustable connection with said casing and bifurcated lower ends fitting upon the walls of the tub adapted to permit

the washing machine to be raised bodily when resistance is encountered by the dasher greater than the weight of the casing and dasher-actuating mechanism.

In testimony whereof, I have signed my name to this specification.

EMILE C. REUTLINGER.
